ADJUSTABLE OUTLET CONVECTOR
ENCLOSUREBenjamin Spieth, Racine, Wis., assignor to
Modine Manufacturing Company, Racine, Wis.,
a corporation of Wisconsin

Application February 5, 1949, Serial No. 74,790

5 Claims. (Cl. 98—40)

1

The invention relates generally to improvements in convector cabinets and, more particularly, to an improved construction for controlling the flow of air therethrough.

The invention has among its objects the production of an adjustable convector cabinet which is very efficient in operation, simple in construction, and which may be economically constructed using modern tools and production methods, and employing a minimum number of parts.

A further object of the invention is the production of such a cabinet in which a movable outlet grille is employed, and which is so constructed that both the size of the air outlet and the effective stack-height of the convector cabinet may be simultaneously varied to control the heat output of the device.

A further object of the invention is the production of a convector cabinet, pleasing in appearance, with the outlet grille being concealed when not in use, and in which the damper or air control structure is very simple but smooth and efficient in operation.

Many other objects and advantages of the construction herein shown and described will be obvious to those skilled in the art from the disclosure herein given.

To this end my invention consists in the novel construction, arrangement, and combination of parts herein shown and described, and more particularly pointed out in the claims.

In the drawings, wherein like reference characters represent like or corresponding parts:

Fig. 1 is a front elevational view of a convector cabinet embodying the present invention, with a portion of the cabinet exterior being broken away to show details of the construction;

Fig. 2 is a sectional view taken approximately on the lines 2—2 of Figs. 1 and 4, respectively;

Fig. 3 is a sectional view taken approximately on the lines 3—3 of Figs. 1 and 2, respectively;

Fig. 4 is a sectional view taken approximately on the line 4—4 of Fig. 2; and

Fig. 5 is a sectional view of the upper portion of the cabinet similar to Fig. 2 but with the air control in a closed position.

Referring to the drawings, and more particularly to Figs. 1, 2, and 3, 1 indicates generally a convector cabinet having a rear wall 2, end walls 3 and 4, and a front wall or panel 5. The top 6 of the cabinet 1 is curved, as clearly illustrated in Figs. 2 and 5, the cabinet having an opening 7 therein adjacent the top of the cabinet adapted to form the air outlet thereof. As illustrated in Figs. 1 and 2, the front panel 5 of the cabinet terminates short of the bottom of the cabinet to

form an air inlet 8. The cabinet thus far described may be constructed in any suitable manner to achieve the desired results. For example, the front wall 5 preferably may be constructed as a removable panel and, suitably connected to the vertically extending portions 9, illustrated as being formed from the same pieces of material respectively comprising the end walls 3 and 4, as clearly illustrated in Fig. 3, with the back wall 2 being formed from a separate piece of material and secured to flanges 11 at the rear edges of the side walls by welding or other suitable means. Likewise, the top portion 6 may be formed from a separate piece of material secured to the adjacent portions of the flanges 9 carried by the end walls, and to the flange 12 carried by the back wall, by welding or other suitable means.

Movably mounted in the cabinet 1 is a member 13 secured at its opposite ends to arcuate shaped plates 14 and 15, the member 13 being secured to the plates by any suitable means, as for example, spot welding or the like, between the flanges 15 and the respective plates, as indicated at 17. The plates 14 and 15 are pivotally connected to brackets 18 by suitable bolts 19, rivets, or the like.

In the construction illustrated, each bracket 18 is provided with a transversely extending flange 21 secured to the back wall 2 of the enclosure by any suitable means, as for example, spot welding. Thus, in effect, the member 13 is pivotally mounted in the cabinet and rotatable about an axis located adjacent the rear edge of the member 13 and the rear wall of the cabinet.

Extending between the plates 14 and 15 is a grille member indicated generally by the numeral 22, the latter being curved and approximately concentric with the curvature of the top 6 of the cabinet, with the radius of the curvature being slightly less than the distance between the axis of rotation of the element 13 and the lower or front edge 23 of the air outlet opening 7. In the construction illustrated, the grille member 22 is divided into two portions 24 and 25, the portion 24 being positioned below the member 13 and provided with suitable grille openings 26, which may, if desired, be designed to provide an ornamental effect. The portion 25 of the grille member 22 is positioned above the member 13 and is solid in form. It will thus be apparent that by rotating the member 13 and structure associated therewith, either the portion 24 of the grille member or the portion 25 may be positioned in the opening 7. To facilitate manual rotation of the movable structure, the latter may be provided with a suitable handle 27 secured, in the present in-

stance, to the member 22 substantially at the juncture of the portions 24 and 25.

Means is also provided for maintaining the member 13 and structure associated therewith in any of its adjusted positions, which means, in the present embodiment of the invention, comprises an arcuate shaped plate 28 rigidly secured to the movable structure by spot welding, or other suitable means, with the plate 28 extending in a plane substantially perpendicular to the pivotal axis of the air control structure. Carried by the rear wall 2 of the enclosure is a bracket 29, the latter having a flange 31 spot welded to the rear wall 2 with the free end of the bracket 29 positioned adjacent the member 28. Mounted on the bracket 29 is a small plate 32, the inner end of which is provided with a flange 33 terminating in a tongue 34 extending through a co-operating slot in the bracket 29. The plate 32 extends outwardly with its free end positioned adjacent the member 28 but on the side thereof opposite to the adjacent end of the bracket 29 whereby the member 28 is positioned between the ends of the bracket 29 and plate 32. Extending through the plate and bracket is a threaded bolt 35, the head of which may be suitably secured to the plate 32 to prevent rotation of the bolt relative to the plate. Positioned on the bolt 35 are washers 36 and a compression spring 37 positioned therebetween, the compression of which is controlled by a suitable wing nut 38. Thus the member 28 may be pinched between the plate 32 and bracket 29, the pressure depending upon the degree of compression of the spring 37, with the flange 33 of the plate 32 forming a fulcrum for the latter. While I have illustrated only one bracket 29 and plate 32, if desired, the structure could be duplicated at the opposite end of the structure, although satisfactory operation may be obtained by the use of only one. The wing nut 38 and spring 37 is preferably so adjusted that smooth rotation of the grille structure is permitted, with the frictional contact between the member 28, bracket 29, and plate 32 being sufficient to satisfactorily maintain the grille structure in any of its adjusted positions. As the front wall or panel 5 of the enclosure will normally be constructed to permit removal thereof and access to the interior of the enclosure, adjustment of the nut 38 and spring 37 may be readily made.

The enclosure is suitably constructed to receive and support a heating element, indicated generally by the numeral 41, positioned adjacent to and above the air inlet opening 8, the details of the heating element 41 and the supporting structure therefor forming no part of the present invention.

It will be noted from the above description that the air control member 13, in effect, forms the top of the convection stack formed by the enclosure and, as the capacity of such type of convector enclosure increases with an increase of the effective height of the convection stack, the present construction, in effect, provides means for varying not only the size of the air outlet opening, but also the effective height of the convection stack. Thus, as the grille structure and member 13 is rotated from the closed position illustrated in Fig. 5 upwardly to expose the grille openings, the distance between the heating element 41 and the top of the air outlet opening is increased simultaneously with the increase in effective size of such air opening, so that when the grille structure is in its open position illustrated in Fig. 2, the height of the convection stack has been increased by approximately the height

of the portion 24. It will be noted that when the grille structure is in a closed position, the solid portion 25 of the member 22 is positioned across the opening 7, thus completely closing the same to present a neat and pleasing appearance, as well as prevent dust and dirt from entering the enclosure.

While I have illustrated the invention in connection with an enclosure or cabinet having a curved top portion, it is believed apparent that the invention may be employed in connection with enclosures having a top portion of different shapes and, if desired, the invention could be employed in such a manner that the member 13 also forms the top of the cabinet, as well as the top of the convection stack.

Having thus described my invention, it is obvious that various immaterial modifications may be made in the same without departing from the spirit of my invention; hence, I do not wish to be understood as limiting myself to the exact form, construction, arrangement, and combination of parts herein shown and described or uses mentioned.

What I claim as new and desire to secure by Letters Patent is:

1. In a convector enclosure, the combination of a cabinet having an air inlet therein adjacent the lower portion thereof and an opening therein adjacent the top thereof, said cabinet being adapted to receive and support a heating element therein with such element positioned intermediate said inlet and said opening, a modulating damper member movably mounted in said cabinet and adapted to form a closure for the opening in the cabinet and also forming the end of the circulation stack formed by the cabinet, said damper pivotally mounted contiguous to the rear wall of the cabinet, an edge of said modulating damper member being movable relative to an edge of said opening to define an air outlet therebetween varying in size dependent upon the position of the modulating damper member, an ornamental grille element operatively mounted on and movable with said damper member positioned adjacent said edge thereof and adapted to extend across the air outlet so formed, movement of said modulating damper member being operative to increase the effective size of the air outlet and to direct the flow of air therethrough and simultaneously increase the effective stack height of the cabinet, with the heating element being spaced from said opening a sufficient distance to permit the grille, when in its closed position, to be positioned substantially within said cabinet, and means including an arcuate shaped member operatively mounted on said modulating damper member, and biasing means complementally formed to the arcuate shaped member and operatively mounted on the cabinet for maintaining said modulating damper in any of its adjusted positions.

2. In a convector enclosure, the combination of a cabinet having an air inlet therein adjacent the lower portion thereof, and an opening in the upper portion thereof, said cabinet having front and rear walls and being adapted to receive and support a heating element therein, with such element positioned intermediate said inlet and said opening, a transversely extending modulating damper member forming a closure for the cabinet and pivotally mounted upon said cabinet and also forming the top of the circulation stack formed by said cabinet, said modulating damper member being rotatable on a horizontal axis

located adjacent the rear wall of the cabinet and extending substantially parallel with the front face thereof, whereby the front edge of said modulating damper member may be rotated upwardly to define a generally vertically extending air outlet and a curved ornamental grille element operatively mounted on and movable with said modulating damper member and adapted to extend across such air outlet as said modulating damper member is rotated, upward rotation of the modulating damper member being operative to simultaneously increase the size of the air outlet and the effective stack height of the cabinet and also to direct the flow of air therethrough, and means including an arcuate shaped member operatively mounted on said modulating damper member and biasing means comprising a support extending forwardly with respect to the rear wall, operatively mounted on the cabinet and operatively mounted with respect to said arcuate shaped member for maintaining said modulating damper member in any of its adjusted positions, with the heating element being spaced from said opening a sufficient distance to permit the grille, when in its closed position, to be positioned substantially within said cabinet.

3. In a convector enclosure, the combination of a cabinet having an air inlet therein adjacent the lower portion thereof, and an opening therein adjacent the top thereof, said cabinet being adapted to receive and support a heating element therein, with such element positioned intermediate said inlet and said opening, a transversely extending modulating damper member forming a closure for the cabinet and pivotally mounted upon said cabinet and forming the top of the circulation stack formed by said cabinet, said modulating damper member being rotatable on a horizontal axis located adjacent the rear wall of the cabinet and extending substantially parallel with the front face thereof, whereby the front edge of said member may be rotated upwardly to define a generally vertically extending air outlet and a curved grille element operatively mounted upon said modulating damper member and movable with said modulating damper and adapted to extend across such air outlet as said modulating damper member is rotated, upward rotation of said modulating damper member being operative to simultaneously increase the size of the air outlet and the effective stack height of the cabinet and also to direct the flow of air through the air outlet, with the heating element being spaced from said opening a sufficient distance to permit the grille, when in its closed position, to be positioned substantially within said cabinet, and means including biasing means comprising an arcuate shaped member operatively mounted on said modulating damper for maintaining said modulating damper in any of its adjusted positions.

4. In a convector enclosure, the combination of a cabinet having an air inlet therein adjacent the lower portion thereof, and an opening therein adjacent the top thereof, the top of said cabinet being curved, said cabinet being adapted to receive and support a heating element therein, with such element positioned intermediate said inlet and said opening, a substantially flat transversely extending member and an arcuate member adapted to form a modulating damper and closure for the opening, said transversely extending member pivotally mounted in said cabinet and forming the top of the circulation stack formed by said cabinet, said members being

rotatable together on a horizontal axis located adjacent the rear wall of the cabinet and extending substantially parallel with the front face thereof, whereby the front edge of said transversely extending member may be rotated upwardly to define a generally vertically extending air outlet and a curved grille element operatively mounted on said transversely extending member movable therewith and adapted to extend across such air outlet as said transversely extending member is rotated, the center of curvature of said grille element being approximately on said horizontal axis, upward rotation of said transversely extending member being operative to simultaneously increase the size of the air outlet and the effective stack height of the cabinet and also to direct the flow of air through the air outlet, and friction means for maintaining said transversely extending member in any of its adjusted positions, with the heating element being spaced from said opening a sufficient distance to permit the grille, when in its closed position, to be positioned substantially within said cabinet.

5. In a convector enclosure, the combination of a cabinet having openings therein for the circulation of air therethrough, one of said openings being variable in size, said cabinet being adapted to receive and support a heating element therein with said heating element positioned intermediate said openings, a modulating damper element forming the variable size opening and an ornamental closure therefor, said modulating damper element being movable relative to said cabinet with an edge of said damper element being co-operative with an edge of said opening to define the variable size opening and to direct the flow of air through the cabinet, the size of which is dependent upon the position of said damper element relative to said opening, a grille structure operatively mounted on and movable with said damper element and also adapted to extend across the variable size opening so formed, whereby movement of the modulating damper element adjusts the size of the opening and directs the flow of air therethrough, and in the closed position of the damper element serves as a closure for the opening, and frictional means including an arcuate shaped member and spring biased means operatively mounted on the cabinet and modulating damper element for retaining said damper element in any of its adjusted positions.

BENJAMIN SPIETH.
